UNITED STATES PATENT OFFICE.

MARY E. FIELD, OF NEW HAVEN, CONNECTICUT.

CORSET.

SPECIFICATION forming part of Letters Patent No. 252,935, dated January 31, 1882.

Application filed September 3, 1881. (Model.)

To all whom it may concern:

Be it known that I, M. EMMA FIELD, of New Haven, in the county of New Haven and State of Connecticut, have invented certain new and useful Improvements in Corsets; and I do hereby declare that the following is a full, clear, and exact description of the invention, which will enable others skilled in the art to which it appertains to make and use the same, reference being had to the accompanying drawings, which form a part of this specification.

Figure 1 is a perspective view of my improved corset. Fig. 2 is a top view of the same, and Fig. 3 is a detail view of one of the bosom-pieces.

Corresponding parts in the several figures are denoted by like letters of reference.

This invention relates to corsets or under-waists for ladies and misses; and it consists in certain improvements in the construction of the same, which will be hereinafter fully described, and particularly pointed out in the claim.

In the waist and back pieces of my improved corset, which said pieces are denoted respectively by the letters A and B, no novelty is herein claimed. The former are provided with thin flexible steels or stays having hooks and eyes of any well-known construction, while the latter are connected in the usual manner by lacing.

The parts A and B are connected to the lower edge of a yoke, C, the shoulder-straps D of which are severed at E and connected by lacing F, which permit the garment to be adjusted to the figure and size of the wearer, so that the strain upon the shoulders may be borne without inconvenience. The lacing F is near the front of the shoulder-straps, so that it may

be conveniently adjusted after the garment has 40 been put on.

The bosom-pieces G are inserted in the front of the yoke, above the front pieces, A, as shown. Said bosom-pieces are each constructed of two pieces of thin, porous, and flexible, but durable, material, connected by a central vertical seam and gathered at the sides, as shown at H. Somewhat similar bosom-pieces have been heretofore constructed of a single piece gathered at the top and bottom; but by this construction a much better fitting and more durable article is obtained.

The waist part of my improved corset is to be corded or stiffened in any suitable well-known manner.

I am aware of the patent to Frost and Phelps, No. 169,899, November 16, 1875, and I claim nothing therein shown; nor do I claim separately the laced shoulder-straps; but,

Having thus described my invention, I claim 60 and desire to secure by Letters Patent of the United States—

In a corset, the combination of the body A B, the yoke C, of the form shown, having laced shoulder-straps, and the bosom-pieces G, each 65 consisting of two pieces of thin porous material united by a central vertical seam gathered at the sides and evenly secured at the top and bottom, all constructed and arranged substantially as herein described, for the purpose set forth.

In testimony that I claim the foregoing as my own I have hereto affixed my signature in presence of two witnesses.

MARY EMMA FIELD.
